CLAIM

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region in FIG. 2; and,

FIG. 10 is an enlarged detail view of the encircled region in FIG. 2.

The dot-dash broken line circles in FIG. 2 delineate portions of the case for electronic communications device that are parts of the claimed design and that are shown on enlarged scales in FIG. 9 and FIG. 10.
